Abraham Norton
Sellers Patent

The Schedule referred to in this Sellers Patent and making part of the same containing a description in the words of the said Abraham Norton himself of his "Inventory App'd."

This press which is capable of considerable variety in form, may when simple be constructed as follows, and is then applicable to the pressing of cheese and all substances to which the usual pressure is applied. Upon two horizontal posts placed so far apart as to allow the required length of bench, and the pressing beam hereafter mentioned to extend between them, are two vertical posts of the height necessary to support the machinery. The bench or support for the articles to be pressed is nearest the bottom and extends between the upright posts above mentioned, their tops being connected by a horizontal girder or brace. In one of these upright posts is a vertical mortise to receive one end of the pressing beam, which is kept in its place while pressing by a triangular or tapering wedge that passes through the mortise above the beam. The pressing beam has a tenon at one end, which goes into the mortise of the post above mentioned where it rests, and is confined by the wedge, this part of the post supporting it as a fulcrum. The pressing beam is of such length as to extend across the press, its opposite end rising and falling in a mortise or groove in the other upright post so as to keep it steady when raised or lowered by the lever herein described. There is a mortise through this pressing beam through which rises the upper end of the follower or presser. This follower also goes through a mortise in the upper girder so as to preserve downward motion. The pressing beam lays upon a projecting shoulder in the press or follower, so that as it descends it bears down the presser with it, and by means of a pin which goes horizontally through the beam and presser, the latter rises as the beam is elevated from the article which has been subjected to pressure. Then the presser lies the lever by which the power is applied. A fulcrum or pivot is set up, passing through the vertical post above the mortise end of the pressing beam. This fulcrum is like a staple held one foot ^{upright} from the post through the lever toward the center of the machinery required distance according to the power wanted where it receives a crank connected with the movable end of the pressing. So that as the lever is raised or depressed it raises or bears down the end of the pressing beam connected therewith and thereby the presser is lifted, which is between the end of the pressing beam that moves and the end which

1663X

is kept stationary by the wedge above it. The face of which is a weight suspended by a cord passing over a pulley at the extremity of the lever farthest from the fulcrum. As this lever descends, the point of the crane which connects it with the pressing beam comes towards a direct line between the place of its being attached to the beam and the fulcrum of the lever, thereby increasing its power, which is a principle in the construction of this press, and from which its name of increasing press is derived. One end of the cord which supports the weight passes round a small cylinder near the bottom of the press and to which a crane is applied for winding it up, or the contrary, so that by turning it the weight is elevated from the floor and bears on the lever by passing over the pulley at its extremity. On the contrary when it is necessary to take off the pressure the weight is suffered to descend to the floor, and that end of the lever to rise, the wedge is withdrawn from above the fulcrum of the pressing beam and the cylinder or press is elevated. The principle of this press may be applied to act in all directions, vertical, horizontal and inclinate, and its power increased in any ratio agreeably to the object to which it may be applied.
